CLAIM

The ornamental design for an ice cream bar toy, as shown and described.

DESCRIPTION

FIG. 1 is a front perspective view of an ice cream bar toy, according to our new design;

FIG. 2 is a back perspective view of the ice cream bar toy of FIG. 1;

FIG. 3 is a front elevation view of the ice cream bar toy of FIG. 1;

FIG. 4 is a back elevation view of the ice cream bar toy of FIG. 1;

FIG. 5 is a left side elevation view of the ice cream bar toy of FIG. 1;

FIG. 6 is a right side elevation view of the ice cream bar toy of FIG. 1;

FIG. 7 is a top plan view of the ice cream bar toy of FIG. 1; and,

FIG. 8 is a bottom plan view of the ice cream bar toy of FIG. 1.

Broken lines, where present, illustrate portions of the ice cream bar toy that form no part of the claimed design.

1 Claim, 7 Drawing Sheets
